W. H. WALLACE.
BASE BALL GAME APPARATUS.
APPLICATION FILED JUNE 11, 1915.

1,185,741.

Patented June 6, 1916.

UNITED STATES PATENT OFFICE.

WILLIAM H. WALLACE, OF PITTSBURG, KANSAS.

BASE-BALL-GAME APPARATUS.

1,185,741.

Specification of Letters Patent. Patented June 6, 1916.

Application filed June 11, 1915. Serial No. 33,425.

To all whom it may concern:

Be it known that I, WILLIAM H. WALLACE, citizen of the United States, residing at Pittsburg, in the county of Crawford and State of Kansas, have invented certain new and useful Improvements in Base-Ball-Game Apparatus, of which the following is a specification.

My invention relates to game apparatus and particularly means whereby a parlor or miniature game of baseball may be played.

The invention aims to provide an effective form of means for discharging the ball over the field or diamond at different angles, consisting in the novel construction, combination and arrangement of the parts as hereinafter described and claimed as well as illustrated in accompanying drawings.

20 In said drawings, which illustrate a preferred embodiment, Figure 1 is a top or plan view of the entire apparatus; Fig. 2 is a cross sectional view on the line 2—2 of Fig. 1; Fig. 3 is a cross sectional view on the line 3—3 of Fig. 2; Fig. 4 is a cross sectional view on the line 4—4 of Fig. 3, and Fig. 5 is a fragmentary plan view of the turnable discharge head.

Referring specifically to the drawings, 30 I represent a suitable baseball diamond as on a board 1 which may have a marginal wall 2 projecting above the top surface thereof. Since any suitable form of board or field may be used, detailed description of this element will be omitted. At the home plate, suitable discharge means generally designated A is arranged in order to project the ball or projectile 3, (see Fig. 4) over the diamond.

40 Means A comprises a head 4 which is pivotally mounted for horizontal movement by means of a bolt 5 passing through an aperture in board 1 and an aperture 6 in the bottom or base wall 7 of the head. Also 45 mounted from the board 1 is an eccentric 8 adapted to be turned in any suitable manner, for instance, by means of a spring motor 9 with the shaft 10 of which the eccentric 8 is connected.

50 A pitman 11 is pivotally connected at 12 to eccentric 8 and at 13 to the head 4. Spring motor 9 during operation, rotates eccentric 8 in order to reciprocate pitman 11 and oscillate the head 4 so that in conjunction with the remainder of mechanism

A, the discharged balls 3 may travel at different angles from the home plate.

Head 4 has side walls in separated relation which are designated 14 and extend upwardly from wall 7. Between the walls 14 a vertically disposed supply chute 15 is suitably fastened. Directly in the rear of chute 15, a rod 16 bridges the walls 14 and is fastened to the upper edges thereof as by means of staples 17. A bat 18 is pivotally mounted on rod 16. At the discharge portion of bat 18 a contact element 19 is provided to directly engage the ball 3 and which is preferably made of rubber, felt or other sound-reducing material. Bat 18 is normally maintained with element 19 in its foremost position by means of a coil spring 20 having an arm 21 connected to the bat and an arm 22 connected to one wall 14 by means of a staple 23. At the rear face, bat 18 has an eyelet or staple 24. Bridging the walls 14 and substantially centrally spaced thereon by means of disks 25, is a rod 26 on which is pivotally mounted a detent lever 26 having an arm 27 provided with a hook 28 to engage the staple 24. Inclined face 28' of hook 28 moves into automatic engagement with staple 24 during movement in one direction. From arm 27, the lever extends rearwardly, upwardly and forwardly, and then terminates in an upstanding lug or finger piece 29. This detent lever is normally in its lowermost position, with hook 28 and staple 24 disengaged, and resting on a rod 30, urged by a spring having a coil 31, an arm 32 fastened to base 7 and an arm 33 exerting upward pressure on the lever at the rear.

Means common to both the bat and detent lever is employed to operate them and is preferably formed of rod material so as to have an arcuate operating portion 34 disposed intermediate and so as to contact during its movement, with lug 29 and the upper portion of bat 18. The operating member has vertical arms 35 depending from portion 34 and from which outwardly extend arms 36 and 37 which are pivotally mounted in bearings 38 fastened to board 1. Arm 37 terminates in an operating handle or crank 39.

In order to prevent the ball 3 rolling from the head 4 accidentally, a guard 40 in the nature of a spring having several coils at its lower end, is fastened to the chute 15.

This spring at its coils is adapted to normally extend below the uppermost point of the ball so that the ball cannot accidentally roll off the head past the spring 40. However, when the bat drives the ball from the head, this spring readily yields outwardly so that the ball may pass the same.

Preferably a means is provided so that the players cannot see the different positions 10 of the head 4 during its oscillation and therefore cannot discharge the ball intentionally to desired points on the diamond. This means, preferably, consists in a housing having a top wall 41 provided with an 15 opening 42 through which chute 15 projects and turns, and with side walls 43 and a rear wall 44. An abutment 45 is secured to the board 1 to be engaged by wall 44 to enable ready positioning of the housing, since it is 20 detachable from the board. Also, suitable hooks 46 may be pivoted as at 47 to the walls 43 and be engageable with eyelets 48 secured to board 1.

With the spring motor 9 in operation, 25 eccentric 8 and pitman 11 cause continuous horizontal oscillation of the head 4. Prior to this movement or during its continuance, one or more balls 3 are deposited in the chute 15, and prevented from accidental 30 escape through the medium of the yieldable guard 40. Prior to discharge of the ball, crank 39 is moved forwardly toward the chute 15 which causes the bat 18 to tilt and the staple 24 to move against the inclined face 28' of hook 28 to thereby raise 35 the hook and cause it to assume the position shown in Fig. 4 where it detains the bat in rearmost position since it overlaps the staple. Even with the parts in this position, 40 the head 4 can turn since arcuate portion 34 has been provided. In order to discharge the ball, crank 39 is again operated, but in a direction away from the chute 15 and during this movement, it contacts with lug 29, 45 causing the detent lever to elevate at its forward end and the hook 28 to disengage the staple 24, whereupon spring 22 spends its energy, causing the bat to forcibly strike the ball 3, rolling it past the yieldable guard 50 40 and on to the diamond. The usual rules for playing baseball, may be substantially observed in scoring runs, in connection with suitable designations on the diamond. After 55 the ball has been discharged, bat 18 may be brought into position for a succeeding discharge, by moving crank 39 forwardly so that portion 34 engages the bat, tilting it, and causing automatic engaging of the hook

28 and staple 24, so that upon reverse movement of crank 39, the detent 26 will be 60 operated for further discharging action.

Since merely the preferred embodiment has been illustrated and described, it is to be understood that changes in the details of construction may be resorted to within the 65 spirit and scope of the appended claims.

I claim:

1. In game apparatus, a turnable head, a receiving chute carried thereby, projectile-impelling means carried by the head and 70 operating means for said projectile-impelling means having a portion to engage the projectile-impelling means, and said portion being deflected to accommodate its mounting near the said receiving chute. 75

2. In game apparatus, a head, a projectile-receiving chute thereon, means to turn said head, a bat, a spring associated with said bat, a detent for said bat, a spring associated with said detent, and an operating member 80 having a portion intermediate the bat and detent to engage the bat and detent, said portion being deflected to accommodate its mounting near the chute.

3. In game apparatus, a head, means to 85 turn said head, said head having upstanding spaced walls, a projectile-supply chute mounted intermediate said walls, a bat, means to pivotally mount said bat upon said walls, a spring connected to the bat and to 90 one of said walls, a detent, means to pivotally mount said detent upon said walls, said detent having a lug thereon, said detent having a hook thereon, means on the bat engageable by said hook, a spring mounted 95 on the head associated with said detent, a rest member for said detent, and operating means having a portion disposed intermediate the bat and the lug of the detent.

4. In game apparatus, a head, means to 100 swingingly move said head, said head having upstanding spaced walls, a projectile supply chute mounted by said walls, a bat, means to mount said bat upon said walls, means to prevent accidental disengagement 105 of a projectile from the head, means to urge the bat into engagement with the projectile, means mounted upon said walls to maintain the bat in projected position, and means to shift the last mentioned means. 110

In testimony whereof I affix my signature in presence of two witnesses.

WILLIAM H. WALLACE.
